UNITED STATES PATENT OFFICE.

A. L. AUGUST SCHIERMEYER, OF DAYKIN, NEBRASKA.

CORN-PLANTER.

SPECIFICATION forming part of Letters Patent No. 379,989, dated March 27, 1888.

Application filed December 30, 1887. Serial No. 259,408. (No model.)

To all whom it may concern:

Be it known that I, A. L. AUGUST SCHIERMEYER, a citizen of the United States, residing at Daykin, in the county of Jefferson and State of Nebraska, have invented a new and useful Improvement in Corn-Planters, of which the following is a specification.

The invention relates to improvements in corn-planters; and it consists in the construction and novel combination of parts herein-after described, illustrated in the accompanying drawings, and pointed out in the claims hereto appended.

In the drawings, Figure 1 is a perspective view of a planter embodying the invention. Fig. 2 is a longitudinal section of the same on the line $x-x$ of Fig. 1. Fig. 3 is a central vertical section of one of the seed-boxes and the parts contained therein. Fig. 4 is one of the seed-box blanks spread flat.

Referring to the drawings by letter, A designates the main frame of the machine, having the axle B journaled in the side rails thereof, and the wheels b b fixed upon and rotating the axle.

C is a tappet secured upon the axle at a convenient point, and provided with the three equidistant equal-sized and similar arms c.

D is the seat, secured on its support d in the central line of the main frame and upon a longitudinal beam, b', thereof aligned with the tongue b², which has its heel secured to and below the front end of said beam.

E are scraper-blades secured to the ends of the transverse shaft e, which is journaled in bearings e' e', secured to the rear ends of the side rails of the main frame.

F is a lever pivoted to the beam b' in convenient position to be pressed down by the foot of the driver, and f is a rod connecting the upper end of said lever to the end of an arm, f', standing up from the shaft e. By pressing down the said lever the driver can, by means of the rod f and arm f', bring the edges of the scraper-blades against the peripheries of the wheels to clean the latter.

G is the seed-frame, provided with the similar rearwardly-extending arms gg' at equal distances on each side of its center, which arms are provided at their ends with bearings g' g', through which passes the shaft H,

journaled in bearings h h h, secured to the side rails of the main frame and to the heel of the tongue.

I is a transverse rail of the seed-frame G, 55 and i is a metal loop rising therefrom and embracing the tongue, so as to limit the swing of the seed-frame on the main frame.

J J are the seed-boxes, each made of a rectangular blank, j, having the four outer trapezoidal portions, j', and the arms j'', converging together from said portions, as shown in Fig. 4. Depending from the bottom of each seed-box is a dropping-tube, K, with its edges converging downwardly, and having secured to 65 its front edge the runner or furrow-opener K'.

L is a shaft having its end portions journaled in the sides of the dropping-tubes on each side, and having mounted upon it, within each of said tubes, a wheel, M, that fits in and 70 closes the open bottom of the corresponding seed-box, and is provided in its periphery with the equidistant seed-recesses m, for the purpose of turning the seed into the dropping-tube below.

N is a ratchet-wheel fixed on the shaft L, and n is a bifurcated arm journaled on the shaft at its end and straddling the ratchet-wheel. n' is a spring-pawl attached to said arm and engaging the ratchet-wheel. The 80 lower or outer end of the arm n is pivoted to the front end of the link-rod O, the rear end of which is pivoted to the depending bifurcated arm p of the angle-lever P, journaled through its angle on the shaft H, and with its 85 upper arm, P', standing rearward in position to be struck and moved downward by the arms of the tappet C as the axle rotates.

p' is a coiled spring, having one end secured to the angle-lever P and the other end to the 90 bearing h of the adjacent arm g of the seed-frame. The said spring is arranged to lift the arm P' when the tappet-arm has passed below the latter. When the said arm P' is depressed by the tappet-arm, the arm p is lifted, and, by 95 means of the link-rod O, arm n, ratchet-wheel N, and spring-pawl n', the recessed wheels in the dropping-tubes are partly turned and a planting takes place.

The wheels M may be arranged to plant simultaneously or alternately, as desired.

Q is a double-armed bent detent-lever, piv-

oted at its angle q on a bracket, R, secured to the front end of the beam b' of the main frame, with its front arm, q' , entering the loop i and its rear upwardly-inclined arm, q^2 , within easy reach of the foot of the driver. The said lever is capable of a slight amount of lateral motion on its pivotal point, and has one edge of its rear arm beveled to form a detent-edge, r , which is adapted to engage the vertical rack R' , that is secured to the beam in front of the seat-supports b' . By means of said double-armed lever and rack the driver can with his foot lift the seed-frame on the main frame to regulate the depth of planting.

15 The machine as described is of simple and strong construction, effective and certain in use, and can be operated readily and with ease.

Having described my invention, I claim—
20 1. The combination of the main frame, the axle, the tappet on the axle, the seed-frame, the shaft H, hinging said frame to the main frame, the shaft L, mounted in the seed-frame and carrying the planting-wheels, the ratchet-wheel on the shaft L, the angle-lever on the shaft H, engaged by the tappet, and the link connected to said angle-lever and carrying a pawl engaging the ratchet-wheel, as set forth.

2. In a planter, the combination, with the 25 seed-boxes, dropping-tubes, furrow-openers, shaft L, journaled upon the seed-frame, planting-wheels M, having the equidistant seed-recesses m , and the ratchet-wheel fixed on said shaft, of the bifurcated arm N, turning loosely

on the shaft L, the spring-pawl n' , the pivoted 35 link-rod O, the double-armed angle-lever P, turning loosely on the shaft H, the coiled spring p^2 , and the three equidistant armed tappet on the axle, substantially as specified.

3. In a planter, the combination, with the 40 main frame, the shaft H, journaled in the side rails thereof, and the tongue, of the seed-frame having rearwardly-extending arms pivoted on said shaft, the loop i , secured to the seed-frame and extending over the tongue, and the double-45 armed lever Q, pivoted upon a bracket secured to the main frame and with the end of its front arm engaging in the loop i , substantially as specified.

4. In a planter, the combination, with the 45 main frame, the shaft H, journaled in the side rails thereof, and the tongue, of the seed-frame having rearwardly-extending arms pivoted on said shaft, the loop i , secured to the seed-frame and extending over the tongue, the 50 double-armed lever Q, pivoted on a bracket secured to the main frame and having the detent-edge r , and the vertical rack R' , secured to the main frame and engaged by the detent-edge r of the lever Q, substantially as speci- 55 fied.

In testimony that I claim the foregoing as my own I have hereto affixed my signature in presence of two witnesses.

A. L. AUGUST SCHIERMEYER.
